UNITED STATES PATENT OFFICE.

JOHN E. WINCHESTER, OF CHARLOTTE, NORTH CAROLINA.

LOCOMOTIVE VALVE-GEAR.

1,146,678.

Specification of Letters Patent. Patented July 13, 1915.

Application filed February 19, 1915. Serial No. 9,396.

To all whom it may concern:

Be it known that I, JOHN E. WINCHESTER, a citizen of the United States, residing at Charlotte, in the county of Mecklenburg 5 and State of North Carolina, have invented certain new and useful Improvements in Locomotive Valve-Gears; and I do hereby declare the following to be a full, clear, and exact description of the invention, such as 10 will enable others skilled in the art to which it appertains to make and use the same.

This invention relates to improvements in locomotive valve gear.

The object of the present invention is to 15 improve the construction of locomotive valve gear and to provide an exceedingly simple, practical and efficient valve gear designed for use on locomotives and other steam engines and capable of affording a variable 20 cut-off and of enabling the valve to remain absolutely stationary when the reversing mechanism is in the central position.

With these and other objects in view the invention consists in the construction and 25 novel combination and arrangement of parts hereinafter fully described, illustrated in the accompanying drawings and pointed out in the claims hereto appended, it being understood that various changes in the form, 30 proportion and minor details of construction may be resorted to without departing from the spirit or sacrificing any of the advantages of the invention.

Figure 1 is a side elevation of a valve 35 gear constructed in accordance with this invention and shown applied to a portion of a locomotive, Fig. 2 is a similar view showing the reversing mechanism of the valve gear in a different position from Fig. 1, and Fig. 3 40 is a transverse sectional view on line 3—3 of Fig. 1.

Like numerals of reference designate corresponding parts in all of the figures of the drawings.

45 In the accompanying drawings in which is illustrated the preferred embodiment of the invention, 1 designates a bell crank fulcrumed at its angle on a pin 2 or other suitable pivot in the horizontal plane of the 50 valve stem 3 of the locomotive and having one of its arms 4 arranged to swing upwardly and downwardly to points above and below the horizontal plane of the valve stem 3. The pin 2 which constitutes the pivot of 55 the bell crank is mounted in a suitable bear-

ing 5 which is bolted or otherwise secured to an arm or standard 6 but the bell crank may be mounted in any other desired manner. The arm 4 which extends forwardly from the pivot of the bell crank carries a 60 radius link 7 pivoted at its forward end to the outer end of the arm 4 by a pin 8 or other suitable fastening device and extending rearwardly from the pivot. The radius link is pivotally connected at its rear end by a pin 9 or 65 other suitable fastening device to the rear end of a link-rod 10 which is connected with the valve stem 3. The arm 4 of the bell crank and the radius link 7 constitute a reverse or reversing mechanism which is exceedingly simple as it is adapted to dispense with the radius yoke ordinarily employed and when the rear end of the radius link occupies the position above or below the horizontal plane of the valve stem, the oscillatory movement of the bell crank through the radius link is adapted to reciprocate the valve in the usual manner. This construction provides a variable cut-off and when the arm of the bell crank is in a central position with the pivot 8 in alignment with the pin 2 and the valve stem 3, the valve will remain absolutely stationary.

Vibratory motion is imparted to the bell crank by an eccentric rod 11 pivotally connected at its rear end by a pin 12 to an auxiliary crank 13 of the axle 14 of the main drive wheel 15 of the locomotive and having an upturned forward end 16 which is pivoted by a pin 17 or other suitable fastening 85 device to a depending arm 18 of the bell crank 1. Various other means, however, may be employed for actuating the eccentric rod and when the eccentric rod is reciprocated the depending arm 18 of the bell crank 90 will be oscillated in a backward and forward direction.

The radius link is supported at its rear end by an approximately vertical link rod 19 connected at its upper end to the radius 100 link by the pin 9 extending therefrom to a rearwardly extending arm 20 of a rock shaft 21 which is designed to extend entirely across the frame of the locomotive. The rock shaft 21 which is journaled in suitable 105 bearings is equipped with a forwardly extending weighted counterbalancing arm 22 and it is provided with an upwardly extending operating arm 23 which is connected at its upper end by a reach rod 24 with a re- 110

versing lever, (not shown). The forwardly extending counterbalancing arm 22 is equipped with a slidble weight 25 adapted to be secured at different distances from the shaft by set screws 26 or other suitable fastening means. The upper end of the arm 23 of the transverse shaft 21 is adapted to oscillate through an arc indicated by the line "a" and when the said arm 23 occupies a central vertical position, the rear pivot of the radius link coincides with the pivot of the bell crank and the reversing mechanism is in a central position with the valve stationary. When the arm 23 is swung to a point in advance of its central position the valve gear is in forward motion and when the said arm 23 is carried to a point in rear of the said central position the valve gear is in backward motion.

20 While the valve gear is designed primarily for use on locomotives it, of course, may be advantageously employed on various types of steam engines.

What is claimed is:—

25 1. A valve gear including a bell crank fulcrumed at its angle in substantially the horizontal plane of the valve stem of an engine and having one of its arms arranged to swing to opposite sides of the said plane, a radius link carried by the said arm of the bell crank and arranged to swing from a central point coincident with the pivot of the bell crank to points at either side of the same to provide a variable cut off, means for 35 adjusting the radius link and means for imparting motion to the bell crank.

2. A valve gear including a bell crank fulcrumed at its angle in substantially the horizontal plane of the valve stem of an engine and having one of its arms arranged to swing to opposite sides of the said plane, a radius link carried by the said arm of the bell crank and arranged to swing from a central point coincident with the pivot of the bell crank to points at either side of the same to provide a variable cut-off, means for adjusting the radius link and an eccentric rod connected with one of the arms of the bell crank for imparting motion to the same.

50 3. A valve gear including a bell crank fulcrumed at its angle in substantially the

horizontal plane of the valve stem of an engine and having one of its arms arranged to swing to opposite sides of the said plane, a radius link carried by the said arm of the bell crank and arranged to swing from a central point coincident with the pivot of the bell crank to points at either side of the same to provide a variable cut-off, means for imparting motion to the bell crank, a 55 shaft having an arm located beneath the radius link, a link rod connecting the arm with the radius link and means for partially rotating the shaft to adjust the radius link.

4. A valve gear including a bell crank fulcrumed at its angle in substantially the horizontal plane of the valve stem of an engine and having one of its arms arranged to swing to opposite sides of the said plane, 60 a radius link carried by the said arm of the bell crank and arranged to swing from a central point coincident with the pivot of the bell crank to points at either side of the same to provide a variable cut-off, means for 65 imparting motion to the bell crank, a counterbalanced shaft having an arm extending beneath the radius link and connected therewith, said shaft being also provided with an upwardly extending operating arm and a reach rod connected to the operating arm.

5. The combination with a valve stem of a bell crank fulcrumed at its angle on a horizontal axis in the rear of the valve stem 85 and having a forwardly extending arm and a depending arm, a radius link pivoted to the forwardly extending arm and extending rearwardly from its pivot, means for connecting the radius link with the valve stem, 90 means for adjusting the radius link upwardly and downwardly above and below a central point coincident with the fulcrum of the bell crank and an eccentric rod connected to the depending arm of the bell 95 crank.

In testimony whereof I affix my signature in presence of two witnesses.

JOHN E. WINCHESTER.
